A. R. RIDDERSTROM

CHANNEL LIP TURNING METHOD

Original Filed Feb. 26, 1920

Patented Oct. 28, 1924.

UNITED STATES PATENT OFFICE.

ANDREW R. RIDDERSTROM, OF NAHANT, MASSACHUSETTS, ASSIGNOR, BY MESNE
ASSIGNMENTS, TO THOMAS C. ROWEN, OF SWAMPSCOTT, MASSACHUSETTS.

CHANNEL-LIP-TURNING METHOD.

Original application filed February 26, 1920, Serial No. 361,532. Divided and this application filed
September 2, 1922. Serial No. 585,909.*To all whom it may concern:*

Be it known that I, ANDREW ROBERT RIDDERSTROM, a citizen of the United States, and resident of Nahant, in the county of Essex and Commonwealth of Massachusetts, have invented a new and useful Improvement in Channel-Lip-Turning Methods, of which the following is a specification.

The present invention relates to channel-lip-turning methods, and more particularly to methods of turning back the channel lips of stiffened soles.

Owing to the great strain to which the channel lip is subjected during the operation of opening and turning it and pressing it flat, the sole must be gripped firmly by the feeding instrumentalities to prevent the sole being pushed bodily away and out of the machine. As the metal stiffener of a stiffened sole is naturally of harder and less yielding quality than the body of the sole, the firm gripping action causes it to bind in the machine, thereby either clogging up and completely stopping the operation of the machine, or else injuring the sole or even the machine parts. It has accordingly been customary hitherto to turn back the channel lip before attaching the stiffener to the sole.

An object of the present invention is to provide an improved method particularly adapted for operation upon stiffened soles.

With the above and other objects in view, the invention consists of the improved method hereinafter described, illustrated in the accompanying drawings and defined in the appended claims.

In the drawings, Fig. 1 is an elevation, partly in section, of a preferred machine adapted to the carrying out of the method of the present invention; Fig. 2 is a detail view showing a preferred yielding connection between the feed wheel and its driving mechanism of the machine shown in Fig. 1; Fig. 3 is a rear elevation of a preferred feed wheel; and Fig. 4 is a perspective view of a shank-stiffened outsole.

The invention is conveniently illustrated in connection with a machine illustrated and described in a copending application, Serial No. 361,532, of which application the present application is a division. Reference may be had to the said application for a clearer understanding of so much of the

machine illustrated in the accompanying drawings, as is not fully explained herein, because unnecessary to an understanding of the present invention. The machine embodies a horizontally rotatable wiper 2 that is adapted to open, turn over and press flat a channel lip 4 of a previously channeled outsole 6, as shown more particularly in Fig. 1. As the lip 4 is subjected to considerable strain during this operation, the sole must be firmly gripped to prevent its being pushed outwardly away from the machine. The desired firm gripping action is effected by a toothed feed wheel 8 on one side of the sole and the wiper and a presser foot 10 upon the other. As the sole is advanced by the feed wheel to the wiper, it is guided by an adjustable guide 12 that lies in the sole channel and bears against the shoulder of the lip, and it is gauged by an adjustable gauge 14.

The present invention is concerned more particularly with methods of operating upon stiffened soles. For the sake of concreteness, a molded, shank-stiffened outsole is illustrated in Fig. 4, the shank stiffener 16 of which extends from the heel to near the ball of the sole. The shank may be applied to the inner face 18 of the sole in any desired manner, as by securing it to the sole at one end 20, as shown, or at both ends. As the shank stiffener is usually of steel or other metal, a material that is much harder than the body of the sole, there is a tendency, owing to the above-described firm gripping action of the feeding instrumentalities, for the sole to wedge in between the elements of the feeding mechanism, resulting either in stopping the operation of the machine or in injuring the outsole or the machine parts.

According to the present invention, this difficulty is overcome by preventing the feed wheel from gripping the shank stiffener. In the illustrative machine, this is effected by making the feed wheel 8 comparatively thin, and mounting it between the guide 12 and the frame of the machine. The feed wheel 8 therefore grips the sole only along the edge, adjacent to the shank stiffener. It is desirable, however, to have the shank stiffener gripped also, and a feature of the present invention contemplates gripping the shank stiffener yieldingly. This is effected

in the illustrative machine by means of a second feed wheel 22, of smaller diameter than the feed wheel 8, mounted adjacent to the feed wheel 8, in side-by-side relation thereto, to engage the shank stiffener 16 yieldingly. The feed wheel 22 is adapted to yield upon pressure being applied to its periphery, as when pressed inwardly by the shank 16. The specific mechanism for rendering the feed wheel 22 yielding will now be described. The feed wheel 8 is provided with a centrally positioned opening 24 (Fig. 1) through which is adapted to enter a boss 26 that is integral with a gear 28 that is rotatably mounted upon an inclined stud 30. The feed wheel 22 is also provided with a centrally positioned opening of greater diameter than that of the boss 26, indicated at 32, whereby it may be loosely mounted upon the boss 26. The feed wheel 8 is thus, in effect, provided with a centrally positioned boss which extends into the opening 32 of the feed wheel 22. The feed wheels are secured against lateral movement along the boss by a securing plate 34. The feed wheel 22 is further provided with radial recesses 36 (Fig. 3) having reduced apertures 38 communicating with the central opening 32. Plungers 40 are mounted in the apertures and are spring pressed into the central opening 32 to engage the boss 26 by springs 42 in the radial recesses. The feed wheel 22 is thus laterally yieldably mounted upon the feed wheel 8, but is normally, when the machine is not operating, yieldingly maintained in central position thereon. The feed wheels are adapted to be rotated as a unit by the gear 28 about the stud 30 by connecting them together, as shown more particularly in Figs. 2 and 3, the feed wheel 22 being provided with a pin 44 that enters a slot 46 in the feed wheel 22. The slot 46 is of larger diameter than the diameter of the pin 44 so as to permit the above-described yielding lateral movement of the feed wheel 22 upon the feed wheel 8.

In operation, the feed wheel 22 yieldingly grips the stiffener shank 16 along the edge, and the feed wheel 8 firmly grips an adjacent edge portion of the face 18 of the sole, the wiper 2 and the presser foot 10 at the same time firmly gripping the other face of the sole at points opposed to the feed wheels. In case too great a strain is placed upon the sole, the shank 16 presses in upon the periphery of the feed wheel 22, causing its surface to yield while the grip upon the sole is still maintained. Very satisfactory operation is thus obtained.

The feed wheel 22 is preferably of slightly smaller diameter than the feed wheel 8 so as to accommodate the extra thickness of the shank 16, as shown in Fig. 1. To provide for a larger bearing surface, the periphery

of the feed wheel 22 may safely be made of greater width than the width of the feed wheel 8. This end is facilitated by conically inclining the peripheral surface of the feed wheel 22, rendering it horizontal at its 70 uppermost position, as shown at 48, to compensate for the inclination of the stud 30. The wings of the wiper 2 incline upwardly away from the wiper-carrying shaft, as shown, so as to cooperate at a suitable angle 75 with the inclined feed wheel 22.

The feed wheel 22 may be of varying thickness, dependent upon the dimensions of the shank of the sole, and its position upon the machine should always be such that the force exerted by the upwardly inclining wings of the wiper, in pressing back the channel lip, shall lie along a line L, Fig. 1, parallel to the feed wheel and approximately midway between its faces. The upper portion of the periphery of the feed wheel 8, consequently, must be positioned between the guide 12 and the frame of the machine. It therefore becomes necessary to vary the position of the feed wheel 8 relatively to the wiper, the presser foot and the guide, depending upon the size and the position of the feed wheel 22. A preferred construction for effecting the desired adjustment of the feed wheels is described in the above-mentioned application, and comprises an eccentric pin 60 of an eccentric post the concentric portion 62 of which is journaled in the frame or support 64 of the machine. Rotative adjustment of the eccentric post will result in adjusting the feed wheels. The feed wheels may thus be adjusted laterally, to the right or to the left (Fig. 1) of the wiper wings, as desired. The eccentric post may be rotatably adjusted by means of a handle 66, and the parts may be clamped thereto by a screw (not shown). The feed wheels may be separated from the wiper, to permit the introduction of a sole, by a treadle 70 acting, in opposition to the force of a torsion spring 72 that is wound about a drum 74, to move the feed wheels downward. Upon the treadle being released, the spring effects a return of the carrier to its normal position. The teeth of rapidly rotating feed wheels have a tendency to bite suddenly, but not deeply, into the sole and, through their high-speed, rotative movement, to cut a groove therein, damaging the sole. To overcome the effects of this damaging tendency, provision is made in the illustrative machine for preventing the feed wheel initially acting upon the sole with its full force. The machine is thus adapted to operate at high speed, but without in any way injuring the leather of the sole. The rotative movement of the driving mechanism is initially not fully transmitted to the feed wheel, its speed becoming thus temporarily 130

slowed down at the moment when it engages the sole, affording it an opportunity to bite deeply into the sole leather before the feeding is resumed at high speed. The feed 5 wheels are so connected to their driving mechanism as to permit a backward yielding rotative movement of the feed wheels relatively to the driving mechanism. The gear 28 is internally grooved at 84 to receive compression springs 86 the ends of which are confined between posts 88 and 90 that are respectively secured to the gear 28 and the feed wheel 8. When a sole is first introduced into the machine, therefore, and the treadle is released, the feed wheels are 10 spring-actuated into engagement with a portion of the sole near the edge and with the shank 16. As the leather is firm enough to overcome the tendency of the springs 84 to keep the feed wheels in the position indicated in Fig. 2, this engagement of the feed wheels by the sole effects a retarding action which causes the feed wheels to slow down or yield backward relatively to the 15 gear 28 of the driving mechanism. The feed wheels are thus forced to assume their normal feeding position, illustrated in Fig. 1, with the springs 84 under tension, and not until they assume this position do they 20 become fully effective to advance the sole at full speed. The sole is, however, advanced, at a slower speed. While the feed wheels are thus slowing down, the feed wheel 8 is afforded an opportunity to bite 25 deeply into the leather and obtain a firm grip thereon, the feed wheel 22 at the same time yieldingly gripping the shank 16, and the presser foot and the wiper firmly gripping the other face of the sole at points opposed to 30 the gripping points of the feed wheels. The force of the spring 72 may be adjusted by a handle 76 that is adapted to rotatably adjust the drum, and the drum may be locked in adjusted position by a spring-pressed 35 plunger 78 acting as a pawl to engage the teeth of a ratchet wheel 80. The plunger 78 may be moved upwardly, in opposition to the force of its spring, so as to release the drum, by a handle 82. 40

It will be understood that the invention is not limited to the exact embodiment thereof that is herein described, but is subject to modification, the scope of the invention being indicated by the appended claims. 45

What is claimed as new is:

1. The method of turning the channel lip of a shank-stiffened sole that comprises yieldingly gripping the shank stiffener and firmly gripping adjacent parts of the sole to feed the sole, and turning the channel lip 55 of the sole as it is fed.
2. The method of turning the channel lip of a sole that is stiffened with a shank stiffener applied to one face thereof that comprises firmly gripping the said face of the sole along an edge, yieldingly gripping the shank stiffener, firmly gripping the other face of the sole, feeding the sole while so gripped, and turning the channel lip of the sole as it is fed. 60
3. The method of turning the channel lip of a sole that is stiffened with a shank stiffener applied to one face thereof that comprises firmly gripping the said face of the sole along an edge adjacent to the shank 65 stiffener but without firmly engaging the shank stiffener, firmly gripping the other face of the sole, feeding the sole while so gripped, and turning the channel lip of the sole as it is fed. 70
4. The method of turning the channel lip of a sole that is stiffened with a shank stiffener applied to one face thereof that comprises firmly gripping the said face of the sole along an edge adjacent to the shank 75 stiffener, firmly gripping the other face of the sole, feeding the sole, while so gripped, first at a comparatively low speed to prevent 80 damaging the sole and then at a comparatively high speed, and turning the channel lip of the sole as it is fed. 85
5. The method of turning the channel lip of a sole that is stiffened with a shank stiffener applied to one face thereof that comprises firmly gripping the said face of the sole along an edge, yieldingly gripping the shank stiffener, firmly gripping the other face of the sole, feeding the sole, while so gripped, first at a comparatively low speed 90 to prevent damaging the sole and then at a comparatively high speed, and turning the channel lip of the sole as it is fed. 95

In testimony whereof, I have hereunto subscribed my name this 1st day of September, 1922.

ANDREW R. RIDDERSTROM.
